Inventor
FRANK ROGERS,

By
Carlton Coulam.

Attorney

UNITED STATES PATENT OFFICE.

FRANK ROGERS, OF SPRINGFIELD, OHIO.

ANTISKID DEVICE.

Application filed April 29, 1927. Serial No. 187,625.

My invention relates to anti-skid devices. It is the object of my invention to provide an anti-skid device particularly adaptable for use on shoes to prevent slipping on ice 5 of such a character that the device will not become loosened from the shoe of the wearer due to the stretching of the strap and the like.

Heretofore, such devices have been largely 10 unsuccessful because of this fact.

It is the object of my invention to provide permanently attached resilient side clamping members attached to the anti-skid plate, which permit the adaptation of the device 15 to various sizes of shoes and to the movements of the shoe without the device becoming loosened from the shoe because no matter how tight the strap may be it will always work loose and the efficiency of the device 20 largely impaired.

Referring to the drawings:

Figure 1 is a side elevation of the device;

Figure 2 is a top plan view thereof;

Figure 3 is a bottom plan view.

Referring to the drawings in detail, 1 is 25 a plate preferably of cast metal having a plurality of sharp depending ground engaging prongs 2, the arrangement of which and number of which may be varied to suit the 30 conditions of the use.

It is customary to use a flat plate 1 when using my device on shoes, but a slightly curved plate may be efficient and desirable in connection with the use on an automobile 35 tire. On either side of the plate is mounted a resilient spring member preferably of wire designated 3 pivotally connected at 4 to the plate 1 and having a loop 5 at its upper end for connection to a rubber strap 6 which may 40 be connected to the end 5 or hook 7 on the opposite spring member 3.

Thus, I have provided three essential elements in my invention: first, a ground gripping plate 1; second, resilient link members 45 3 which are arcuate in form and are adapted to accommodate themselves to the side of the shoe or tire at the same time forming a permanent resilient connection; and, third, a rubber strap 6.

These arcuate resilient wire side members 50 3 pivoted at 4 accommodate the rolling and

rocking of the shoe upon the plate 1 or accommodate the alternate expansion and contraction of the shoe or the tire, while the resilient strap 6 provides for the further 55 accommodation of the foot of the wearer in the comfortable fashion and accommodates the outfit to varying sizes of shoes and sizes of feet.

It will be understood that I desire to comprehend within my invention such modifications as may be necessary to adapt it to varying 60 conditions and uses.

Having thus fully described my invention, what I claim as new and desire to secure by 65 Letters Patent, is:

1. In combination, a stiff anti-skid plate adapted to be secured to the sole of a shoe and having a plurality of sharp projections, wire loops formed so as to be resiliently pivoted on said plate and having a hook on the end thereof, and a strap adapted to be attached to and detached from the said wire hooks, whereby walking on slippery surfaces 70 is facilitated and the danger of falling is 75 minimized.

2. An article of wearing apparel comprising the combination with a shoe of an anti-skid plate detachably secured to the sole of the shoe, arcuate resilient side members pivoted thereto and provided with hooks, and a strap engaging said hooks, connecting the 80 said members and securing the plate to the sole of a shoe.

3. An article of wearing apparel comprising the combination of a shoe, an anti-skid plate detachably secured to the sole of the shoe, arcuate resilient side members with restricted portions formed into hooks pivoted thereto, and a strap engaging said hooks, connecting the said members and securing the plate to the sole of the shoe, the said 85 strap being resilient.

4. In an anti-skid device, a rectangular plate member having anti-skid prongs thereon, a bail-shaped member pivotally mounted at one end of said plate member having a restricted part therein bent to form a hook, a second bail-shaped member pivotally mounted at the other end of said plate and having a restricted part therein bent to form 90 100 a hook, and means engaging said hook mem-

bers to bind the anti-skid device to the object upon which it is used.

5. In an anti-skid device, a rectangular plate member having anti-skid prongs thereon, a bail-shaped member pivotally mounted at one end of said plate member having a restricted part therein bent to form a hook, a second bail-shaped member pivotally

mounted at the other end of said plate and having a restricted part therein bent to form ¹⁰ a hook, and resilient means engaging said hook member to bind the anti-skid device to the object upon which it is used.

In testimony whereof, I affix my signature.

FRANK ROGERS.
